UNITED STATES PATENT OFFICE.

HARRY E. ZOLL, OF PHILADELPHIA, PENNSYLVANIA.

DESIGN FOR A RADIOCABINET.

Application filed March 1, 1924. Serial No. 8,796. Term of patent 14 years.

To all whom it may concern:

Be it known that I, HARRY E. ZOLL, a citizen of the United States, residing at Philadelphia, in the county of Philadelphia and State of Pennsylvania, have invented a new, original, and ornamental Design for a Radiocabinet, of which the following is a specification, reference being had to the accompanying drawing, forming part thereof.

The figure is a perspective view of a radio cabinet showing my new design.

I claim:

The ornamental design for a radiocabinet, as shown.

HARRY E. ZOLL.
